[57] ABSTRACT

A display buffer for controlling lighting of lamps and other functions at a plurality of operator positions. There is an arrangement of relay drivers and relays into what are effectively matrix circuits, with current sensors connected to relay driver ground switches using a common resistor for each bit of status codes (including reset), so that current for only one relay should flow through each resistor. The arrangement includes logic associated with the current sensors to monitor the operation and detect failures.

FIG. 17

CONTROL OF OPERATOR POSITION DISPLAY

BACKGROUND OF THE INVENTION

1. Field of the Invention

This invention relates to a display buffer for controlling lighting of lamps and other functions at a plurality of operator positions.

2. Description of the Prior Art

A display buffer is described in the Bell System Technical Journal, Vol. 49, No. 10, Dec. 1970, pages 2,602-2,603.

SUMMARY OF THE INVENTION

The invention relates to the arrangement of the relay drivers and relays into what are effectively matrix circuits, with current sensors connected to relay driver ground switches using a common resistor for each bit of status codes (including reset), so that current for only one relay should flow through each resistor. The arrangement includes logic associated with the current sensors to monitor the operation and detect failures.

CROSS REFERENCE TO RELATED APPLICATIONS

This invention is included in a TSPS system briefly described in the GTE Automatic Electric Technical Journal, Vol. 12, No. 7, July 1971, pages 276-285.

The central processor and peripheral controller are disclosed in a U.S. Pat. application for Control Complex for TSPS Telephone System, by E. F. Brenski et al., Ser. No. 289,718 filed Sept. 15, 1972.

The data link for communication of data between operator's positions and central control is disclosed in a U.S. application by M. Winn, W. R. Wedmore, and J. S. Young for Data Link Arrangement with Error Checking and Retransmission Control (H-1713), Ser. No. 397,454 filed the same day as this application.

DESCRIPTION OF THE DRAWING

FIG. 1 is a functional block diagram of the decoding and relay driver circuits of the buffer control circuit;

FIGS. 2 and 3 are schematic diagrams of the relay drivers for battery and ground respectively;

FIGS. 4 and 5 are diagrams of relays in the display buffer;

FIG. 6 is a schematic and functional block diagram of a current sensor;

FIGS. 7-9 are functional block logic diagrams; and

FIGS. 10-18 are wave form diagrams for operation of the current sensors and associated logic.

DETAILED DESCRIPTION

As described in the copending data link patent application, the data link has a local terminal at a base location, and a remote terminal at a traffic office which has a maximum of 62 operator positions. Messages received at the remote terminal include a command data with 15 bits B0-B15. A display buffer comprises relays having contacts connected to lamps of the positions. A buffer control circuit is connected between the data set and the display buffer.

The function of the Buffer Control Circuit (BCC) is to accept commands from the RTC (Remote Terminal Circuit), decode them and generate appropriate control signals as required to perform the desired Traffic Office function. In addition, maintenance circuits are pro-

vided to test for the successful completion of most commands to the T.O. The functional and maintenance circuits will be discussed separately.

FUNCTIONAL CIRCUITS

The structure of the incoming commands is basic to the understanding of the BCC. The command consists of 16 bits divided into three fields. The position field (Bits ϕ through 5), the control group field (Bits 6 through 11) and the status code field (Bits 12 through 15).

The Position Field, B ϕ through B5, identifies the position to which the command is addressed with B ϕ as the most significant bit. These positions consists of the 15 62 TSPS Positions numbered 1 through 62 and two psuedo-positions numbered $\phi\phi$ and 63. Commands to position ϕ control the MRG (Maintenance Report Generator) at present; while commands to position 63 control the displays on the administrative cabinets and 20 perform all non-TSPS position control functions in the T.O. other than the MRG. If they should be required position $\phi\phi$ commands could perform additional T.O. control functions.

The control group field, B6 through B11, usually 25 identifies the control group addressed which is associated with the position or psuedo-position addressed in B ϕ through B5. A control group number is binary coded with B6 as the most significant digit. It identifies a set of one or more devices, usually lamps, grouped together for coding efficiency because they can only take on a limited number of states. In most cases a control group consists of a set of lamps only one of which can be lit at any given time. All of the control groups and their functions are shown in Tables 1 through 3. Table 30 1 shows the control group functions for position $\phi\phi$, the MRG. Table 2 shows the control groups for Traffic Service Positions, numbered 1 through 62, and Table 3 shows the control groups for Position 63, the Administrative Cabinet Circuit.

The remaining four bits of the command, B12 through B15, the status code field, describe the state desired for the control group. The number of states which any individual control group can take varies between 1 and 13. These are listed in Tables 1 through 3 as subdivisions of the control group functions. In addition to providing for control of a traffic office with the commands listed in Tables 1 through 3 the BCC can be used as a service observation system controller. For 40 control groups which require more than eight states all four bits of the status field are used. If only 3 bits are required then bits B12 through B14 are used. If two bits, then B12 and B13. Two state control groups only use B12. In general, zeros in the status code indicates reset the control group. The only exceptions to the rule are control groups 6 ϕ and 61 in the Service Observing application.

As shown in FIG. 1, the buffer control circuit BCC is basically a decoding device for the incoming command fields. It is implemented with HTL logic and with 55 Main Ground Switch and Main Battery Switch Discrete Printed Circuit Boards. As can be seen in FIG. 1, the position field is used to drive a one of 64 position decoder generating 64 PD (Position Decode) leads. Since the decoder generates an inverted signal, the PD leads are inverted before being applied to the position drivers. The position drivers are gates B (Main Battery Switches) which switch battery to the output identified

in the position field. The position decoder is enabled by DREN (Driver Enable) and if this signal is absent none of the outputs will be energized. The operation of DREN is further discussed with maintenance circuits later in this section.

The second field, the control group field, is initially handled in the same manner as the position field. B6 through B11, drive a one of 64 decoder identical to the position field decoder. The decoded outputs, called CG (Control Group) leads, are then inverted.

The status code field provides a second source of inputs to the relay driver logic gates. This field again needs to be buffered. In addition, at the buffering stage all zeros in the field (Reset) is detected and brought out as a separate signal, RST. In the Traffic Office application, RST plus the individual bits, B12 through B15, provide all of the inputs other than the CG leads required for the relay driver logic gates. The output of the relay driver logic gates in turn drives the FS (Function Select) relay drivers G which are (Main Ground Switches) which apply grounds at the FS outputs selected by the relays driver logic. This coincidence of battery from the position field and grounds from the remaining fields will then pull in HQA relays in the buffer. The circuits of the main battery switches B and main ground switches G are shown in FIGS. 2 and 3. Note that the ground switch output 25 is connected via a current sensor to ground. This output is shown at the bottom of each switch G in FIG. 1.

Almost all control functions at the T.O. are performed using the PS and FS signal coincidence as described above. There are however three other control interfaces which are different. The first of these is the TMBC control. Here the position field is used to drive MBS switches with outputs RBO through RB5 which then store the position field in an HQA relay register. REGRST, also a battery switch, is used to reset a relay register. MON and TST which are the outputs of ground switches driven by CG44 and CG43 respectively to select one of two registers. The logic inputs necessary to energize the outputs are shown in Table 6. Secondly, there is the RECON-TBLRST logic which provides switched ground on either of the two output leads to control switchover of copies of TOCF. Its logic equation is also shown in Table 6. RCT.CR is the command relay (CR) lead from the data set indicating completion of receipt of message. Finally there are the PSF and RRF leads. Their logic equations are also shown in Table 6. Their output is HTL logic levels. PSF (Position Status Flag) directed to the Key Scanner requests the contents of the key bus of the position identified in the position field. RRF directed to the remote terminal circuit requests retransmission of the message with sequence number in B13 through B15.

DISPLAY BUFFER

FIG. 4 shows the relays of Control group No. 1 of position 1. This group has all four function relays for bits B12-B15 and a reset relay, with ground supplied via leads FS001-FS005 from FIG. 1. These leads are connected in multiple to group No. 1 of all positions. Battery potential is supplied via lead PS01 to all five relays and also to relays of other groups for the same position. As shown in Table 2, a digit display message may have any value from 1 to 0, with bits B12-B15 coded accordingly. When the decoders in FIG. 1 are activated, the selected relays operate, and make before break

contacts (form D indicated by *) disconnect them from the driver leads and lock over a circuit including break contacts of the reset relay. A decoding contact tree connects battery potential for the selected lamp.

- 5 A subsequent message selects and operates the release relay, which locks itself to a path with a parallel connection via make contacts of the function relays to ground. The function relays restore, which then restores the release relay.
- 10 The release relay for this group is also used to release the function relays of groups 2-13 and 42. The locking path for the release relay therefore has parallel connected make contacts on all the function relays of these groups. Because of the number of relays in these groups, the release relay has two break contacts for locking the function relays.

15 FIG. 5 shows the relays of control group 25, position 1, which control a key calling lamp. As shown in Table 2, the lamp may be lit steady with bit B13, or flashing with bits B12 and B13. For flashing, relay MA (bit B12) transfers the battery connection to a 120 IPM source.

BCC MAINTENANCE CIRCUITS

20 The BCC maintenance circuits comprise current sensors and associated logic. The function of the Current Sensor and associated logic is to determine that proper relay operation occurred in the Display Buffer Circuit, a 62 by 141 relay matrix. It accomplishes this by monitoring the current switched by the Function Select MGS circuits, the verticals of the DBCF matrix. Because it is possible for as many as four relays to pull-in at once and as few as one and because the reset relays function differently from the others, the current sensor circuits are subdivided into five separate similar subsystems. One each for the relays associated with Bits B12 through B15 of the command and one for reset relays. We can then conceive of the DBCF matrix as being five submatrices organized so that on any given command at most one and only one relay in each submatrix should pull-in.

25 30 35 40 45 50 System operation can be divided into Current Sensing and trouble detecting by current Sensor Logic. The current sensing circuit is shown on FIG. 6. On an incoming command to a position the appropriate position main battery switch and one of the Function Select main ground switches are switched on. The current pulling in the relay will flow through the emitters of the main ground switches which gets ground through the 10 ohm register, R1, which also provides ground to the emitters of all the other B12 main ground switches output transistors.

55 60 65 The voltage generated across R1 is coupled via C1 of FIG. 6 to a pair of differential amplifiers used as voltage comparators. The low threshold detector has Reference Voltage = 0.13 volts and its output switches from logic ϕ ($= \phi$ volts) to logic 1 (+12 volts) when the voltage across R1 is greater than the reference voltage. The high threshold detector switches from logic ϕ to 1 when the voltage across R1 is greater than the reference voltage = 0.38 volts. Minus 0.13 volts corresponds to 13MA through R1 while 0.38 volts means 38MA. All five current sensor subsystems have identical current sensors.

65 The logic itself can be subdivided into common logic (FIG. 7), B12 through B15 logic (FIG. 8) and Reset logic (FIG. 9). The current Sensor Logic, can best be

understood by considering the waveforms across R1 for normal operation and the various failure modes anticipated. FIG. 10 shows typical waveforms across R1 for normal pull-in in the B12 submatrix based on tests with HQA relays. The figure also shows CR (Command Ready) a nominal 20 MS pulse during which pull-in is required and all other relevant gates and FF's in the logic. The B12 Current Sensor logic FIG. 8 contains four S-R flip-flops (latches) and control gates. The flip-flops are the Inhibit FF, the Normal I FF, the IRZ FF and the CS Trouble FF. In normal operation only the Normal I and the IRZ FF are affected.

The sequence of events after a command with a B12 pull-in arrives is then as follows:

1. The initializing pulse — INITIALIZE, resets the Normal I FF and the IRZ FF at the beginning of a command sequence. The initializing pulse is generated by the HTL monostable in the CS Common Logic shown in FIG. 7 whenever Command Ready (CR) has a positive swing. It resets the Normal I FF and the IRZ FF of all five current sensors logic. Unless a failure occurred on the previous operation both of these flip-flops should be set at the beginning of a command. The waveforms for this and succeeding steps is shown in FIG. 11.
2. The voltage across R1 begins to rise exponentially eventually reaching 130 MV and switching AMP1 output CS1OUTL to 1.
3. CS1OUTL is buffered by the two input NANDS 9 and 11 of FIG. 9. The buffering is necessary because the op amp will only drive 2 HTL logic loads. CS1OUTL is gated by CSEN (current sensor enable), a 2 millisecond pulse which suppresses CS1OUTL as well as all other voltage comparator outputs until switching transients have died down.
4. B12.CS1OUTL is formed at gate 21. The function of this gate is to determine that a relay should be pulled in, B12 = 1, and that it did pull-in, CS1OUTL = 1.
5. Proper pull-in as indicated in four next drives a 3-input "OR" formed of gates 17, 19 and 1. The other inputs to this "OR" will be discussed subsequently as other normal modes of Current Sensor logic operation.
6. The output of the OR is next NANDED in gate 13 with Command Ready (CR) to set the NORMAL I FF, gates 16 and 15. The Normal I FF stores the information that the voltage across R1 exceeded 130 volts, i.e., that the current drawn by the MGS's exceeded 13 MA.
7. The voltage across R1 continues to rise until the relay pulls in at 250 MV $\pm$ 50 as measured in tests with HQA relays. At pull-in the voltage across R1 drops to zero as ground comes back through the NC contact during the bunching period of the form D contact. At this time CS1OUTL drops back to zero. The output of gate 9 goes to 12 volts which when NANDED with Normal I FF in gate 3 and switches on the IRZ FF, gates 18 and 20. IRZ is a mnemonic for Current Returned to Zero.
8. Nothing of further significance occurs through the end of CR (Command Ready) and the 416 μ s period of CR until — INITIALIZE occurs at the next positive swing of Command Ready, starting another sequence. If no B12 submatrix relays are to

be pulled in the waveforms will be as shown in FIG. 10.

After the form D contact bunching period the relay is isolated from the MGS and MBS. Since the MGS is not turned off for B12 through B15 current sensors during the remainder of CR, the leakage current through the 30K resistor in the MGS shown on FIG. 6 will draw approximately 1.5 MA. causing the 1.5 MV drop across R1. This is not enough to switch AMP1 and should have no further effect. The MGS and MBS are left on to test for shorted diodes as described later.

The other normal modes of operation are necessitated by the operation of the IRZ FF. In order to insure that pull-in occurred the IRZ FF must be set before CR drops back to zero. If it is not set gate 26 will switch to zero and set the failure flip-flop, gates 4 and A of FIG. 9 via one of the three remaining inputs to A used as a 3-input trouble "OR." The commonest example of a command which would have this difficulty with the IRZ FF is one where B12 = ϕ as shown in FIG. 11. In this case none of the B12 relays should pull in. The B12 input at gate 17 in this event will simulate normal I and set the NORMAL I FF when CR comes up. Since no MGS should be turned on in this case, CS1OUTL should be = ϕ and the IRZ FF should also be set immediately afterwards.

The third input which sets the Normal I FF is $-C-SINH$. This signal which originates in the CS Common Control logic FIG. 7 is a 7 input "OR" which indicates a message to T.O. Hardware for subsystems other than the Display buffer matrix or a dummy message. These other subsystems are the TMBC (MON or TST), the KSC (PSF or RRF) and SSC (RECON and TBLRST). Key waveforms for this case are shown in FIG. 12.

There are four fault conditions which will set the Current Sensor Trouble FF. These are:

1. Failure to set the IRZ FF during the 20 MS CR period as detected by gate 26. Display Buffer Fault conditions which could cause this are:
  - a. Open output in activated MGS or MBS which would never allow NORMAL I FF to be set.
  - b. Open diode or winding at crosspoint relay which would also never allow NORMAL I FF to be set.
  - c. Active MGS decoder stuck at 1 or Active MBS decoder stuck at ϕ which would also never allow NORMAL I FF to be set.
  - d. A stuck armature on crosspoint relay with resulting failure to eventually isolate coil from MGS during Command Ready.

In any of these faults the waveforms in the Current Sensor system will be as shown in FIG. 13.

2. The next two cases are those which set the INHIBIT FF, gates 6, 7 and 8. This FF is set up by a two input OR formed from gates 5, 1 ϕ and 12. The upper input to the "OR" is CS1OUTH and its primary function is to detect more than one relay pulling in. The relevant CS system waveforms are shown on FIG. 14. The INHIBIT FF is then reset by $-CR$ thereby providing test capability for the next Command. The fact that a failure occurred is stored in the CS1FLR FF through another input to gate A and this failure FF retains the information that a failure occurred until reset by a specific command from base location energizing TBLRST.

Failures which will set CS1OUTH are:

1. Shorted output on MGS or MBS other than the one activated.
  2. Decoder output for MGS other than one activated stuck at 1 or MSB output other than that activated stuck at ϕ .
  3. Shorted turns on crosspoint coil or short in wiring.

The other failure mode which sets the INHIBIT FF is CS1OUTL-B12 = 1 or an attempt to pull in a relay as evidenced by R1 Current greater than 13 MA. when 10 none should be pulled in. The "and" function is performed by gate 12. Fault conditions which could cause this are:

1. Shorted output on an MGS.
  2. Active MGS decoder output stuck at 1.

The associated waveforms are shown on FIG. 15.

The remaining failure mode as detected by gate 25 is I after IRZ. This is mainly intended to detect shorted diodes in the matrix. This is accomplished as can be seen in FIG. 16 by detecting the shunt current through the shorted diode during the time remaining after pull-in of the intended relay. Another fault which will cause the same output is a buzzing relay, with the current now flowing through the coil to be pulled-in and not through a shunt. 20 25

The B13 through B15 submatrix Current Sensor subsystem are identical to the B12 subsystem except that the matrices themselves are smaller. The RST (Reset) submatrix is different from the previous matrices as described in Section 4, but the difference is only in the latching mechanism as is shown on FIG. 17 and does not effect the theory of operation. The RST current sensors and their operation is also identical to that of the B12 through B15, but the RST Current Sensor logic is different in two respects. First, as can be seen in the waveforms for a normal RST pull-in in FIG. 17 DREN (Driver Enable) is cut off as shown as pull-in occurs. This is accomplished by an "OR" of the INHBIT FF and the IRZ FF in gates 25 and 22. The second difference is that the set lead to the INHBIT FF is gated by BIGRST. This signal which is generated in the C.S. Common logic is an "OR" OF all the commands which would pull in more than one Reset relay. These commands will be used at the end of a call to reset all called related displays. Since this is an additional mode of normal operation the waveforms for this case is shown in FIG. 18. Because the drivers are turned off after pull-in, the leakage current observed in the B12 matrix no longer occurs. For this reason also, the shunt current observed in the case of a shorted diode will not occur when pulling in crosspoints of the RST matrix. This is not a serious disability since as shown in FIG. 14 in order to detect the shunt current through the shorted diode it is necessary to pull in a crosspoint with different horizontal and vertical from the defective diode.

This can be accomplished in the B12 through B15 submatrices to test RST crosspoint diodes. The I after IRZ gate is still retained in the RST CS5 logic but its sole function is to detect a buzzing RST relay.

In addition to detecting component failures, the current sensors and logic can be used to interrogate the DBCF and determine the status of crosspoints. This is done by sending a pull in message to each crosspoint immediately followed by a reset of the same crosspoint. If the crosspoint was not latched initially, both of these operations will appear normal. However, if it was latched a trouble message will be generated because

CS1OUTL will never occur and the NORMAL I and consequently the IRZ FF's will never be set.

		$\phi\phi 1\phi$	Remove Alarm 31, TOCF ϕ Power off Key, from MRG Key bus.		
		$\phi\phi\phi 1$	Remove Alarm 32, TOCF1 Power on key, from MRG Key bus.		
9	$\phi\phi 1\phi\phi 1$	1 $\phi\phi\phi$	Remove Alarm 33, TOCF1 Power off key, from MRG Key bus.	15	
		$\phi 1\phi\phi$	Remove Alarm 34, Local test key, from MRG Key bus.		
		$\phi\phi 1\phi$	Remove Alarm 35, TOCF Transfer Key from MRG Key bus.	20	
		$\phi\phi\phi 1$	Remove Alarm 36, Interrupter ϕ failure from MRG Key bus.		
10	$\phi\phi 1\phi 1\phi$	1 $\phi\phi\phi$	Remove Alarm 37, Interrupter 1 failure, from MRG Key bus.	25	
		$\phi 1\phi\phi$	Remove Alarm 38, unassigned, from MRG Key bus.		
		$\phi\phi 1\phi$	Remove Alarm 39, unassigned, from MRG Key bus.		
		$\phi\phi\phi 1$	Remove Alarm 40, unassigned, from MRG Key bus.	30	
11	$\phi\phi 1\phi 1 1$	1 $\phi\phi\phi$	Remove Alarm 41, unassigned, from MRG Key bus.	63	

35

TABLE 1-Continued

CPU COMMANDS FOR POSITION ϕ (MRG)					
CONTROL GROUP NUMBER	CONTROL GROUP CODE	STATUS CODE	B12-B15	B6-B11	FUNCTION
14	$\phi\phi 1 1 1\phi$	$\phi\phi\phi\phi$	Restore all alarms except Alarm 21, MRG card 1 fuse alarm, and Alarm 42, MRG card 2 fuse alarm to MRG Key bus.		
62	111111 ϕ	$\phi\phi\phi\phi$	If MRG card 1 fuse is blown then alarms 1 through 20 cannot reach MRG Key bus.		
		$\phi 1\phi\phi 1$	If MRG card 2 fuse is blown then alarms 22 through 41 cannot reach key bus. Alarms 21 and 42 cannot be removed from MRG Key bus.		
		$\phi\phi 1\phi$	Retransmission Request for message with sequence number 1.		
		$\phi 1 1\phi$	Retransmission Request for message with sequence number 2.		
		$\phi 1 1 1\phi$	Retransmission Request for message with sequence number 3.		
		$\phi 1\phi\phi$	Retransmission Request for message with sequence number 4.		
		$\phi 1\phi 1\phi$	Retransmission Request for message with sequence number 5.		
		$\phi 1 1\phi\phi$	Retransmission Request for message with sequence number 6.		
		$\phi 1 1 1\phi\phi$	Retransmission on Request for message with sequence number 7.		
		1 $\phi\phi\phi$	Return status of MRG key bus to CMC.		

TABLE 2

CONTROL GROUP NUMBER	CONTROL GROUP IDENTIFICATION	CPU Commands for Positions 01 through 62 (In Numerical order).			FUNCTION
		CONTROL GROUP CODE	STATUS CODE	B12-B15	
1	Digit Display & Display Identification Reset	$\phi\phi\phi\phi 1$	$\phi\phi\phi\phi$		Reset all lamps set by Control Groups 1 through 12, 13, 42.
1	Digit Display No. 1	$\phi\phi\phi\phi 1$	$\phi\phi\phi 1$		Light number 1 on digit display.
			$\phi\phi 1\phi$		Light number 2 on digit display.
			$\phi\phi 1 1$		Light number 3 on digit display.
			$\phi 1\phi\phi$		Light number 4 on digit display.
			$\phi 1\phi\phi$		Light number 4 on digit display.
			$\phi 1\phi 1$		Light Number 5 on digit display.
			$\phi 1 1\phi$		Light number 6 on digit display.
			$\phi 1 1 1$		Light number 7 on digit display.
			1 $\phi\phi\phi$		Light number 8 on digit display.
			1 $\phi\phi 1$		Light number 9 on digit display.
			1 $\phi 1\phi$		Light number 0 on digit display.
2	Loop No. 1 Supervisory Reset	$\phi\phi\phi\phi 1\phi$	$\phi\phi\phi\phi$		Reset all lamps set by Control Groups 30, 33, 36.
2	Digit Display No. 2	$\phi\phi\phi\phi 1\phi$	$\phi\phi\phi 1$	through	Same as Control Group No. 1 for digit display No. 2
			1 $\phi 1\phi$		
3	Loop No. 2 Supervisory Reset	$\phi\phi\phi\phi 1 1$	$\phi\phi\phi\phi$		Reset all lamps set by Control Groups 31, 34, 47.
3	Digit Display No. 3	$\phi\phi\phi\phi 1 1$	$\phi\phi\phi 1$	through	Same as Control Group No. 1 for digit display No. 3.
			1 $\phi 1\phi$

13	Call Related Lamp Reset I	001101	0000	Reset all lamps set by Control Gps 18, 2φ, 21, 22, 28, 39, 41 and Reset Bit 13 Cont. Gp. 15 (Flash Class of Charge).	
13	Display Identification	φφ11φ1	φφφ1	Light Hotel Lamp Steady.	
			φφ1φ	Light Spare Lamp Steady.	
			φ1φφ	Light Minute Lamp Steady.	
			φ1φ1	Light Minutes, Hours, Seconds, Lamps Steady.	
			φ11φ	Light Minutes and Charges, Lamps Steady.	
			111φ	Light Minutes and Charges, Lamps Flashing.	
14	Call Related Lamp Reset II	φφ111φ	φφφφ	Reset Control Gps. 14, 16, 17, 23, 24, 25, 29 and Bit B12 Cont. Gp. 15 (Flash Kind of Call).	
14	Kind of Call	φφ111φ	φφφ1	Light Non-Coin Station Lamp.	
			φφ1φ	Light Non-Coin 0+ Lamp.	
			φφ11	Light Non-Coin 0- Lamp.	
			φ1φφ	Light Coin Station Lamp.	
			φ1φ1	Light Coin 0+ Lamp.	
			φ11φ	Light Coin 0- Lamp.	
			1φφφ	Light Hotel Station Lamp.	
			1φφ1	Light Hotel 0+ Lamp.	
			1φ1φ	Light Hotel 0- Lamp.	
15	Class of Charge Flashing Relay	φφ1111	φ1φφ	Flash Control Gp. 28.	
15	Kind of Call Flashing Relay	φφ1111	1φφφ	Flash Control Gp. 14.	
16	Overseas	φ1φφφφ	1φφφ	Light "Overseas" Lamp Steady.	
17	EMG	φ1φφφ1	1φφφ	Light EMG Lamp Steady.	
18	GST Lamp Reset	φ1φφ1φ	φφφφ	Reset Control Group 18, GST Lamp.	
18	GST	φ1φφ1φ	φφφφ	Light GST Lamp Steady.	
19	OGT Lamp Reset	φ1φφ11	φφφφ	Reset all lamps set by Control Group 19, OGT.	
19	OGT	φ1φφ11	φφφ1	Light OGT φ Lamp Steady.	
			φφ1φ	Light OGT 1 Lamp Steady.	
			φφ11	Light OGT 2 Lamp Steady.	
			φ1φφ	Light OGT 3 Lamp Steady.	
			1φφ1	Light OGT φ Lamp Flashing.	
			1φ1φ	Light OGT 1 Lamp Flashing.	
			1φ11	Light OGT 2 Lamp Flashing.	
			11φφ	Light OGT 3 Lamp Flashing.	
2φ	Function Control Lamp Reset	φ1φ1φφ	φφφφ	Reset all lamps set by Control Group 2φ.	
2φ	Function Control	φ1φ1φφ	φφ1φ	Light Ring Back Lamp Steady.	
			φ1φφ	Light Ring FWD Lamp Steady.	
			φ11φ	Light Release Back Lamp Steady.	
			1φφφ	Light Release FWD Lamp Steady.	
			1φ1φ	Light Coin Collect Lamp Steady.	
			1φφ1	Light Coin Return Lamp Steady.	
21	T & C Lamp Reset	φ1φ1φ1	φφφφ	Reset Control Gp. 21, T & C Lamp.	
	T & C Lamp	φ1φ1φ1	1φφφ	Light T & C Lamp Steady.	
22	PCB Lamp Reset	φ1φ11φ	φφφφ	Reset Control Gp. 22, PCB Lamp.	
	PCB Lamp	φ1φ11φ	1φφφ	Light PCB Lamp Steady.	
23	NFY, Charges Due Reset	φ1φ111	φφφφ	Reset all lamps set by Control Gps. 23 and 24.	
	NFY	φ1φ111	φ1φφ	Light NFY Lamp Steady.	
			11φφ	Light NFY Lamp Flashing.	
24	Charges Due Lamp	φ11φφφ	1φφφ	Light Charges Due Lamp Steady.	
25	Key Clg. Lamp Reset	φ11φφ1	φφφφ	Reset Control Group 25, Key Clg. Lamp.	
25	Key Clg.	φ11φφ1	φ1φφ	Light Key Clg. Lamp Steady.	
			11φφ	Light Key Clg. Lamp Flashing.	
26	Make Busy Lamp Reset	φ11φ1φ	0000	Reset Control Group 26, Make Busy Lamp.	

TABLE 2—Continued

CONTROL GROUP NUMBER	CONTROL GROUP IDENTIFICATION	CPU Commands for Positions 01 through 62 (In Numerical order).			FUNCTION
		CONTROL GROUP CODE	STATUS CODE	B12-B15 B6-B11	
26	Make Busy	φ11φ1φ	φ1φφ		Light Make Busy Lamp Steady.
			11φφ		Light Make Busy Lamp Flashing.
27	POS Trans. Lamp Reset	φ11φ11	φφφφ		Reset Control Group 27, POS. Trans. Lamp.
27	Pos. Trans.	φ11φ11	1φφφ		Light Pos. Trans. Lamp Steady.
28	Class of Charge Lamps	φ111φφ	φφφφ		Reset all lamps set by Control Groups 28, 55 and Bit B13 of Control Gp 15.
28	Class of Charge	φ111φφ	φφφ1		Light Station Paid Lamp.
			φφ1φ		Light Station Collect Lamp.
			φφ11		Light Station Special Clg. Lamp.
			φ1φφ		Light Station Special Clg. Lamp.
			φ1φ1		Light Station Auto Collect Lamp.
			φ11φ		Light DDD lamp.
			φ111		Light Person Collect Lamp.
			1φφφ		Light Person Sp. Clg. Lamp.
			1φφ1		Light Person Sp. Clg. Lamp.
29	Timing Lamps Reset	φ111φ1	1φ1φ		Light NO ATT Lamp.
29	Timing	φ111φ1	φφφφ		Reset all lamps set by Control Group 29.
			φφφ1		Light Cancel Timing Lamp Steady.
			φφ1φ		Light Start Timing Lamp Steady.
			φφ11		Light Start Timing Lamp Steady.
			φ1φφ		Light Record Message Lamp Steady.
			1φ11		Light Start Timing Lamp Flashing.
30	Loop No. 1 Hold & ACC Lamps	φ1111φ	φφφφ		Reset all lamps set by Control Group 3φ.
30	Loop No. 1 Supervisory	φ1111φ	φ1φφ		Light ACC Lamp Steady for Loop NO. 1.
			φ11φ		Light Hold Lamp Steady for Loop No. 1.
			1φφφ		Light ACC Lamp Flashing for Loop No. 1.
			111φ		Light Hold Lamp Flashing for Loop No. 1.
31	Loop No. 2 Hold & ACC Lamps	φ11111	φφφφ		Reset all lamps set by Control Group 31.
31	Loop No. 2 Supervisory	φ11111	φ1φφ		Light ACC Lamp Steady for Loop No. 2.
			φ11φ		Light Hold Lamp Steady for Loop No. 2.
			1φφφ		Light ACC Lamp Flashing for Loop No. 2.
			111φ		Light Hold Lamp Flashing for Loop No. 2.
32	Loop No. 3 Hold & ACC Lamps	1φφφφφ	φφφφ		Reset all lamps set by Control Group 32.
32	Loop No. 3 Supervisory	1φφφφφ	φ1φφ		Light ACC Lamp Steady for Loop No. 3.
			φ11φ		Light Hold Lamp Steady for Loop No. 3.
			1φφφ		Light ACC Lamp Flashing for Loop No. 3.
			111φ		Light Hold Lamp Flashing for Loop No. 3.
33	Loop No. 1 Clg.	1φφφφ1	φφφφ		Reset all lamps set by Control Group 33.
33	Loop No. 1 Clg.	1φφφφ1	1φφφ		Light Loop No. 1 Clg. Lamp Steady.
34	Loop No. 2 Clg.	1φφφ1φ	φφφφ		Reset Control Group 34, Loop NO. 2 Clg.
34	Loop No. 2 Clg.	1φφφ1φ	1φφφ		Light Loop No. 2 Clg. Lamp Steady.
35	Loop No. 3 Clg. Lamps.	1φφφ11	φφφφ		Reset Control Group 35, Loop No. 3 CLD.
35	Loop No. 3 Clg.	1φφφ11	1φφφ		Light Loop No. 3 Clg. Lamp Steady.
36	Loop No. 1 Clg.	1φφ1φφ	φφφφ		Reset Control Group 36, Loop No. 1 Clg.
36	Loop No. 1 Clg.	1φφ1φφ	φ1φφ		Light Loop No. 1 Clg. Lamp Steady.
			1φφφ		Light Loop No. 1 Clg. Lamp Flashing.
37	Loop No. 2 Clg. Lamp	1φφ1φ1	φφφφ		Reset Control Group 37, Loop No. 2 Clg.

CPU COMMANDS FOR POSITION 63 (ACTIVE COPY)					
CONTROL	CONTROL	STATUS			
GROUP	GROUP	CODE	B12-B15		
NUMBER	CODE	B12-B15			
B6-B11			FUNCTION		
54	11φ11φ	φφφφ	Reset SSC trouble relays and all CS fail FF's on active TOCF.		

NOTE: The following CPU commands are intended for Position 63 (Standby Copy) only.

1	φφφφφ1	1φφφ	Pull B12 twice pull test relay (Used to test B12 current sensors logic by pulling in the same relay twice without an intervening reset).	10
		φ1φφ	Pull B13 twice pull test relay (Used to test B13 current sensor logic by pulling in the same B13 relay twice without an intervening reset).	15
		φφ1φ	Pull B14 twice pull test relay (Used to test B14 current sensor logic by pulling in the same B14 relay twice without an intervening reset).	20
		φφφ1	Pull B15 twice test relay (Used to test B15 current sensor logic by pulling in the same B15 relay twice without an intervening reset).	25
		φφφφ	Reset all B12-B15 twice pull test relays.	
11	φφ1φ11	1φφφ	Pull in two B12 test relays to test B12 current high detector and current Sensor Logic.	
		φ1φφ	Pull in two B13 test relays to test B13 Current high detector and Current Sensor Logic.	30
11	φφ1φ11	φφ1φ	Pull in two B14 test relays to test B14 Current high detector and Current Sensor Logic.	
		φφφ1	Pul in two B15 test relays to test B15 Current high detector and Current Sensor Logic.	35
25	φ11φφ1	φφφφ	Reset all paired B12 to B15 test relays used for Current high tests. Reset RST twice pull relay (Control Group 26).	
26	φ11φ1φ	φφφφ	Pull RST twice pull test relay (used to test RST current sensor logic by trying to pull in the same relay after first latching it up.)	45
27	φ11φ11	1φφφ	Enable Standby Key Scanner to collect Position Keying indications.	
		φφφφ	Disable Standby Key Scanner from collecting Position Keying indications.	
35	1φφφ11	φφφφ	Pull in two RST test relays to test RST current high detector and Current Sensor Logic.	50
37	1φφ1φ1	φφφφ	Reset RST test relay pair used for current high tests.	
39	1φ1φφ1	1φφφ	Pull in a B12 relay with three HQA relays across it to simulate a shorted diode and test B12 Current Sensor Logic.	55
		φ1φφ	Pull in a B13 relay with 3 HQA relays across it to simulate a shorted diode and test B13 Current Sensor Logic.	60
		φφ1φ	Pull in a B14 relay with 3 HQA relays across it to simulate a shorted diode and test B14 Current Sensor Logic.	
		φφφ1	Pull in a B15 relay with 3 HQA relays across it to simulate a shorted diode and test B15 Current Sensor Logic.	65

vidual output of the position decoder, each first switch device being enabled when its position decoder output is selected to supply a first potential to an individual position select lead;

a decoding gate having inputs from all N status bit leads and an output to a reset status lead to provide a true signal condition on the reset status lead when all N of the status bits are zero;

a control group decoder having inputs from the leads for the control group field and outputs to control group leads of which one at a time is selected when the decoder is enabled;

a plurality of second switch devices, each having an enabling input, a source input, and an output to an individual function select lead, the input of each second switch device being coupled to the output of a function select gate having an input from a control group lead and an input from a status lead, organized into N + 1 status groups, all of the second switch devices in the same status group having their function select gates with an input to the same status bit lead, which for one group is the reset status lead, the source leads of all second switch devices being connected to a multiple point, with a resistor connected between the multiple point and a source of second potential, so that a second switch device when enabled supplies the second potential from the source via the resistor to its function select lead;

R14	= CG14-RST
CG(n)	= Control Group Number, Decoded Bits 6 to 11 (See Table 4)
SD(n)	= Status Decode Number, Decoded Bits 12 to 15 (See Table 5)
RTC-CR	= Command Ready Flag From RTC

What is claimed is:

1. A display buffer and control circuit for operating display devices and performing other functions at a plurality of positions in accordance with commands received on a set of leads, in commands having a format comprising a position field, a control group field, and a status field, each field comprising a plurality of bits with a lead for each bit in said set, there being N bits in the status field;

a position decoder having inputs from the leads for the position field and outputs of which one at a time is selected when the decoder is enabled, a plurality of first switch devices equal to the number of positions, each having an input coupled to an indi-

45 a decode enable lead connected to said position and control group decoders to normally enable them in response to a command ready signal;

50 a plurality of relays for each position organized into control groups, with at least 1 and not more than N function relays in each control group, and normally including also a reset relay, each relay having a winding and contacts, with one end of the winding coupled to a position select lead and the other end coupled via an isolation diode to a function select lead, each function relay having contacts which when the relay is operated disconnect it from the position select and function select leads and connect it to a locking path which includes break contacts of a reset relay usually in the same control group, and the reset relay having contacts which disconnect it from the position select lead and connect it to a locking path which includes make contacts in parallel for all of the function relays of the control group, so that when the reset relay is selected and operates, it releases the function relays and is then itself released when the function relays have restored, contacts of the function

23

relays connected to operate display devices according to a code of the status bits of each control group;
 an individual current sensor for each said status group coupled to said resistor of its status group to sense the current through the resistor, each current sensor having a high output lead with means to supply a high signal thereon if the current exceeds a first threshold level, and a low output lead with means to supply a low signal thereon if the current exceeds a second lower threshold level, the normal current being as drawn by one relay being between the two threshold levels,
 and logic means with connections to said output leads of the current sensors to detect and indicate various normal and abnormal conditions.
 2. A circuit as claimed in claim 1, wherein for some control groups no reset relay is provided, and the lock-

24

ing path for the function relays is via break contacts of the reset relay of another control group for the same position.

3. A circuit as claimed in claim 2, wherein the reset status group of second switch devices includes some for which the function select gate is enabled in accordance with the signal condition on a plurality of control group leads.

10 4. A circuit as claimed in claim 3, wherein said logic means includes means to disable certain responses to the reset current sensor for situations in which a plurality of reset relays are operated in response to the same command.

15 5. A circuit as claimed in claim 1, wherein the abnormal conditions include some resulting from defective isolation diodes.
